UNITED STATES PATENT OFFICE.

LIONEL W. RICHARDSON, OF ROSCOE, ILLINOIS.

MOP-WRINGER.

SPECIFICATION forming part of Letters Patent No. 660,201, dated October 23, 1900.

Application filed March 17, 1900. Serial No. 9,042. (No model.)

To all whom it may concern:

Be it known that I, LIONEL W. RICHARDSON, a citizen of the United States, residing at Roscoe, in the county of Winnebago and State of Illinois, have invented certain new and useful Improvements in Mop-Wringers, of which the following is a specification.

The object of this invention is to construct a mop-wringer in which the mop is placed between jaws which are automatically operated by a downward movement of the mop and are brought together, thereby expelling the water from the mop.

In the accompanying drawings, Figure 1 is an end view of my improved mop-wringer with the parts in their normal position. Fig. 2 is a side elevation. Fig. 3 is an end elevation showing the parts in the position they occupy when the mop is being wrung.

A standard E is supported upon legs C and has a vertical opening, within which is located a guide D, adapted to move in a vertical direction. To the upper end of this guide are pivotally connected two jaws A by the bolt a. The lower ends of the jaws are pivotally connected with the legs c of the standard by links B in such a manner that the links cross each other, and as the guide D is moved downward the links will cause the lower ends of the jaws to spread and their upper ends to close, when these parts will assume the position shown at Fig. 3. The upper ends of the jaws A are provided with fingers, forming a receptacle, within which is placed the mop.

The lower end of the guide E has a cross-bar G connected thereto, and the ends of this cross-bar are turned down, forming ears, and are perforated.

A spring F is coiled around a pin supported by the ears of the cross-bar G. The ends of the spring are formed with eyes d, into which are hooked links H, having their ends located in recesses e, formed in the legs of the standard.

Fig. 1 shows the wringer in its normal position, and it is designed to be placed in a pail or other receptacle holding water.

The mop is placed within the receptacle formed by the jaws A, and a downward pressure on the mop-handle will force the receptacle downward, and by reason of the link connection between the jaws and the legs of the standard the jaws will be forced toward each other, thereby expelling the water from the mop, and the spaces between the fingers of the receptacle allow the water to run into the pail within which the wringer is placed. In lifting the mop from the receptacle the spring connection between the guide and standard will raise the guide and through the link connection will spread the jaws into their normal position, as shown at Fig. 1.

I claim as my invention—

1. In a mop-wringer, the combination of a support, a guide supported thereby, a pair of jaws supported by the guide forming a receptacle to receive a mop, and means forming a connection between the jaws and support whereby the downward movement of the mop located between the jaws will cause the jaws to press against it.

2. In a mop-wringer, the combination of a support, a guide supported thereby, a pair of jaws pivotally supported by the guide, links connecting the jaws and support, and a spring connection between the guide and support.

3. In a mop-wringer, the combination of a support, a guide movable in the support, a pair of jaws pivotally supported by the guide, links connecting the jaws and support, and a spring connection between the guide and support.

LIONEL W. RICHARDSON.
